WASHING MACHINE

Bernhart A. Benson, Chicago, Ill., assignor to
Chicago Electric Manufacturing Company, Chi-
cago, Ill., a corporation of Illinois

Application November 19, 1937, Serial No. 175,450

4 Claims. (Cl. 68—132)

The present invention relates to a washing machine and more particularly to a device of the class wherein an agitator is employed to assist in removing dirt from articles to be washed by creating a turbulence in the washing fluid.

It is an important object in the present invention to provide a washing machine of extreme simplicity of construction and having a minimum of parts which occupy a relatively small space during use as well as during periods of storage or inactivity.

The present invention comprehends the provision of a washing machine which is free from an excess multiplicity or complexity of supports, driving mechanisms, motors and accessories. Many devices heretofore proposed in the present art comprise a relatively intricate as well as heavy assembly of parts which occupy more space than can be frequently spared in modern dwellings. Moreover, the structure often necessitates the use of packing glands and other mechanical elements which may be the cause of leakage and mechanical difficulties.

The present invention, therefore, has for an additional object to provide a washing machine wherein all of the driving parts are mounted in a light, compact unit upon the cover portion and are arranged above normal liquid level in the washer, thus being completely protected from damage thereby.

A yet further object of the present invention is to provide a washing machine in which the driving mechanism is rigidly formed and attached to the cover of the machine and arranged well above the washing zone in normal use, but which, when it is desired to store the device, may be readily disassembled by simple separation of the parts and rearranged so that the driving means is within the confines of the part which, in use, corresponds to the washing zone in order to protect the parts and occupy a minimum of storage space.

Other objects of the present invention are to provide a simple and improved means for providing oscillating movement to the agitator which may be made a rigid part of the cover of the device; to provide improved, releasable, supporting and drive means for the agitator which is automatically engageable in driving relationship to the agitator when the cover is applied in operative relation and wherein the driving connection is made from above liquid level; and to further provide a washing machine having a vessel for accommodating the articles to be washed which is light and simple in structure

and which may be readily filled and/or emptied by the operator during the process of washing.

Numerous other objects and advantages will more fully appear during the course and progress of the following specification.

Referring to the drawings:

Figure 1 is a perspective view of a washing machine constructed in accordance with the present invention.

Figure 2 is a sectional elevation taken on the line 2—2 in Figure 1.

Figure 3 is a sectional elevation substantially the same as Figure 2, but showing the parts as rearranged during periods of inactivity.

Figure 4 is a detail sectional elevation taken on the line 4—4 in Figure 2.

Figure 5 is a sectional plan view taken on the line 5—5 in Figure 4.

Figure 6 is a view taken the same as Figure 5 but with the parts of the drive mechanism in a different operative position.

Figure 7 is a perspective view of the oscillating gear sector shown in Figures 5 and 6.

The device, shown for the purpose of illustrating the present invention, comprises a suitable vessel to support and enclose the articles to be washed as well as the washing liquid and having a cylindrical upstanding wall 10 closed at the lower end by the bottom wall 12. The upper open end of the wall 10 is turned over to form a rounded bead 14 in order to provide a gently curved seat for the cover.

Centrally of the bottom wall 12 there is mounted the pivot 16 which is rigidly secured in place by means of the nut 18 or by any other suitable fastening means. This pivot serves to support the agitator 20 for pivotal oscillatory movement within the surrounding vessel in order to create proper turbulence to carry out the washing action. The agitator comprises a central cylindrical column 22 bored at the bottom as at 24 to provide a bearing surface properly fitting the upstanding surface of the pivot 16. The agitator is further provided with a bell-shaped lower standard portion 26 and a plurality of radially extending vanes, in the present structure three in number. It will be noted that the agitator, as clearly shown in Figure 2, is supported in spaced relationship from the bottom wall 12 of the surrounding vessel by means of the annular flange which may be integrally formed with the pivot.

Attention is directed to the fact that the open upper end of the washing liquid containing vessel may be closed by a cover unit which contains,

not only the driving motor means and the transmission means, but is also provided with an automatic, releasable connection for transmitting oscillatory movement to the agitator 20 when the cover is in operative position. The cover proper, indicated by the numeral 32, is preferably slightly concave on its inner surface, being depressed centrally, as shown in Figures 1 to 3, for a purpose which will hereinafter appear.

An annular shoulder 34 formed in the cover member 32 confers strength and rigidity and is integral with the further flat, radially extending section 36 terminating in an upwardly and reversely extending shoulder or flange portion 38. It will be noted that the flange portion is so formed at the lower portions of the cover member 32, when in the operative position shown in Figure 2, as to normally reside below the upper edge of the bead 14, thus securely centering the cover in position, while the outwardly extending portion of the flange rests upon the top of the bead.

The cover is permitted to seat uniformly upon the bead 14 and to maintain an even and efficient seal therewith by means of the annular rim member 40 which is desirably of some soft material and, in the preferred embodiment, of an elastic, resilient, substance like rubber. It will be noted that this rim member comprises an upper portion 42 which extends inwardly to enclose the top of the flange 38 and a lower, inwardly extending portion 44 which is situated between the lower portion of the flange 38 and the adjacent supporting bead 14, as shown in Figure 2. Since the rim member, as shown in Figure 2, may be an integral, one-piece unit, it will be obvious that, after being slipped over the flange 38 with the portions 42 and 44 extending on either side thereof, it will remain securely in the position shown in the figures and will provide a resilient, cushioned seal for the cover.

The driving and transmission unit 46 is mounted in a relatively large central aperture in the cover, as will be apparent from a consideration of Figures 2 and 4, and comprises a cylindrical casing 48 closed adjacent the bottom by a wall 50, being of increased width adjacent its upper portions to provide the annular shoulder 52 which rests against the upper surface of the cover member 32 and permits securement of the driving assembly thereto through the agency of the bolts 54. The bolts 54 also pass through a flange formed on the lower portion of the motor housing 56 as well as through a partition member 58 which serves to separate the motor housing and the transmission mechanism. A pair of washers 60 which are preferably of some resilient material have the function, not only of sealing the unit from the ingress of exterior dirt and moisture, but provide a substantially resilient support which tends to absorb any motor vibration.

The power delivered by the drive shaft 62 of the motor is first transmitted through a suitable speed reduction gear train, shown in detail in Figures 4 to 6, and comprising a pinion 64 driving the gear 66 mounted upon the pivot 68 which is rigidly secured to the supporting partition 58. The gear 70 integral with the gear 66 in turn drives the gear 72 which is mounted upon a similar pivot 74 and integral with the gear 76. The gear 76, operating at a reduced rotational speed, meshes with the gear 78.

It will be apparent, after viewing Figures 4 to 6, that the gear 78 is supported upon a pivot 80

rigidly mounted in the supporting partition 82 which in turn is secured by three machine screws 84 to suitable embossments 86 circumferentially spaced about the interior of the casing 48. It will be noted that the supporting partition 82 is suitably apertured to permit the gear 76 to extend therethrough. The gear 78 thus rotationally mounted upon the pivot 80 is provided with an embossment 88 spaced radially from the center of rotation to which is secured the link or connecting rod 90 by means of the pivot 92 threadedly mounted therein. The connecting rod 90, at its other end, is pivotally secured to the sector gear 94, shown in detail in Figures 4 to 7 inclusive. The sector gear is slotted and provided with an insert 96 secured removably in place by the machine screw 98, which insert extends radially outwardly beyond the outer surface formed by the teeth of the gear in order to support the bushing 100 in which is secured the threaded pivot 102 which engages the end of the connecting rod 90. The sector gear 94 is in turn mounted for rotation upon the fixed pivot 104 fastened to the bottom wall 50 of the enclosing casing by means of a nut 106, as shown in Figure 4.

According to the present embodiment, the gears and links are so formed and arranged that rotational movement of the gear 78 transmits oscillatory movement to the sector gear 94 through a predetermined arc of rotation. The oscillatory rotation is directly transmitted to the shaft through a gear 108 which is rigidly pinned to the drive shaft 110 whereby this drive shaft is caused to continuously reverse its movement after a predetermined arc of rotation. It will be noted that the gear or pinion 108 is arcuately relieved as at 112 in order to permit passage of the radially outwardly extending insert 96 during its normal path of movement.

The drive shaft 110 is mounted in the downwardly projecting embossment integrally formed with the bottom wall 50 of the casing 114 and providing a stuffing box or packing seal therefor. The packing gland 116 surrounding the shaft 110 is threaded therein and comprises a suitable mass of packing material so that any liquid caused to splash about the end of the drive shaft 110 will be prevented from entering the driving mechanism.

According to the present invention a simple, readily releasable connection is provided between the upper end of the agitator and the drive shaft. To this end the lower end of the drive shaft 116 is provided with a polygonal bushing 118 rigidly pinned thereto while the upper end of the cylindrical column 22 of the agitator is bored as at 120 to provide a mating polygonal configuration into which the bushing 118 will automatically engage when the cover is applied in operative position to the device. It will be readily apparent that the bushing and mating aperture may be hexagonal, as shown in the figures, or may possess any other suitable configuration to provide a rotational driving connection therebetween.

It will be obvious from the above disclosure that the present device comprises three freely separable units, namely, the cover, the agitator and the washing liquid containing vessel. When it is desired to place the machine in operation, the agitator is situated over the pivot, as shown in Figure 2, after which the articles to be washed, together with a suitable washing liquid, are placed thereabout. The cover unit is then placed upon the vessel, as shown in Figure 2, at which time the bushing 118 will reside in the aperture 120.

in the upper end of the agitator in driving engagement. The electrical conduit 122 which supplies electricity for operating the driving motor is next connected to a suitable source of electric current at which time the motor shaft 62 commences to rotate, driving the gear 76 through the speed reducing gear train. Rotation of the gear 78 in turn causes transmission of reciprocatory movement to the gear sector 94 through the agency of the driving link or connecting rod 90. The oscillatory movement so produced is transmitted through the agency of the gear 108 and the drive shaft 110 to the agitator which thus is caused to rotate through a predetermined arc about the pivot 16 and then to continuously reverse its direction of movement after completing this path of travel. It is by this means that agitation of the washing liquid within the vessel is maintained in order to loosen the dirt from the articles to be washed.

Referring more specifically to Figure 3, it will be apparent that the machine constructed in accordance with the present invention may be, during periods of disuse, stored with the normally projecting portions of the cover within the cylindrical walls 18 of the washing vessel. Thus, if the agitator is lifted from its pivot and permitted to reside upon its side, as shown in Figure 3, the cover may be reversed and rested upon the bead 14 in a normally upside down relation. In this position, the structure, not only occupies little more space than the confines of the washing vessel, but provides a protecting enclosure for the working mechanism and particularly the motor. With the cover in this position it will be noted that what is normally the upper surface 42 of the rim member 40 coacts with the annular bead 14 to provide a resilient seat or cushion.

The present invention provides a simple and compact washing machine which may be readily lifted or conveyed by the operator and may be stored in a minimum of space. The present structure, in permitting the omission of relatively heavy structural parts, moreover, admits of ready emptying or filling with washing or rinsing fluid and greatly facilitates cleaning thereof after the washing operation is completed.

Opposed handle members 124 may be formed on the outer cylindrical wall 18 of the vessel in order to permit carrying and emptying thereof while a pair of similar handles 126 are preferably attached to the cover to permit its removal or situation in operative position.

Attention is further directed to the fact that with all of the driving parts mounted as a unit upon the cover, any repairs or adjustments of the mechanism are necessarily limited to this unit with the result that the remaining portions of the structure need not be disturbed. This structure, furthermore, does away with the necessity for apertures below normal fluid level through which leakage or damage of the driving mechanism may occur and results in a situation of the working parts at an elevated position where they cannot be reached by destructive moisture.

It is thought that the invention and numerous of its attendant advantages will be understood from the foregoing description and it is obvious that numerous changes may be made in the form, construction and arrangement of the several parts without departing from the spirit or scope of the invention, or sacrificing any of its attendant advantages, the form herein described

being a preferred embodiment for the purpose of illustrating the invention.

The invention is hereby claimed as follows:

1. In a washing machine, a container, an agitator in said container, a cover for said container, said cover being symmetrical about a central, vertical axis and having a central, convex-concave portion with the convex side facing upwardly, a motor, an agitator drive shaft, a transmission mechanism between said motor and said drive shaft, a releasable coupling between said drive shaft and said agitator, a housing for said transmission mechanism from which housing said agitator drive shaft depends, the convex-concave portion of the cover having a centrally disposed aperture therein, said housing being mounted in said aperture and secured to said cover, said motor being mounted on said housing on an axis of symmetry of the cover and extending above said cover, and a hood enclosing said motor and secured to said housing.

2. In a washing machine, a cylindrical pot, an agitator on the axis of the pot, a disk-shaped cover, said cover having a centrally disposed convex-concave portion with the convex side facing upwardly, said portion having an aperture therethrough centrally thereof, a housing extending through said aperture and having a peripheral flange overlying the edge of the aperture in the cover, a motor mounted on said housing on the coincident axis of the cover and pot with its shaft extending into the housing, an agitator drive shaft depending from said housing, a releasable coupling between said shaft and said agitator, transmission mechanism in said housing and connecting the motor to the agitator drive shaft, and a hood for the motor, said hood being mounted on the housing, and common means for securing the hood and housing to the cover.

3. In a washing machine, a container, an agitator, a cover symmetrical about a central, vertical axis, said cover having a centrally disposed convex-concave portion with the convex side facing outwardly, said portion of the cover having an aperture extending therethrough centrally thereof, an upwardly opening cup-shaped housing member extending through said aperture and having a peripheral flange overlying the edge of the aperture in the cover, a plate carried by said flange and closing said cup-shaped housing member, a motor mounted on said plate on the vertical axis of symmetry of the cover with the shaft extending through the plate into the housing member, an agitator drive shaft depending from said housing member, a releasable coupling between said shaft and said agitator, a gear train in said housing member connecting the motor shaft to the agitator drive shaft, a hood for the motor mounted on the edge of said plate overlying the peripheral flange of the housing member, common fastening elements passing through the cover, the peripheral flange of the housing member and the hood, securing the hood, housing member and plate to the cover, and sealing members interposed between the peripheral flange of the housing member and the plate and between the plate and the hood.

4. A washing machine comprising a container symmetrical about a central, vertical axis, an agitator operable about said axis, a cover symmetrical about a central, vertical axis co-incident with the axis of symmetry of the container, said cover having an aperture therethrough centrally thereof, a separate casing let into said aperture.

and rigidly secured to said cover, a motor mounted on said casing on a vertical axis co-incident with the axes of symmetry of the cover and container, an agitator drive shaft depending from said casing member, a releasable coupling between said drive shaft and said agitator, trans-

mission mechanism in said casing member and connecting the motor to the agitator drive shaft, and a hood for the motor symmetrical about the axis of the motor and secured to said casing member.

BERNHART A. BENSON.
